INVENTOR,

John H. Mumaw,

BY Frease, Mankel, Saywell and Bond

ATTORNEYS.

UNITED STATES PATENT OFFICE.

JOHN H. MUMAW, OF PITTSBURGH, PENNSYLVANIA.

DESIGN FOR A VEST FOR LADIES' BLOUSES.

60,874.

Specification for Design. Patented Apr. 18, 1922.

Application filed December 17, 1918. Serial No. 267,222. Term of patent 3½ years.

To all whom it may concern:

Be it known that I, JOHN H. MUMAW, a citizen of the United States, residing at North Side, Pittsburgh, in the county of Allegheny and State of Pennsylvania, have invented a new, original, and ornamental Design for a Vest for Ladies' Blouses, of which the following is a specification, reference being had to the accompanying drawing, forming part thereof.

In the drawing:

The figure shows a garment embodying my new design for garment closure.

I claim:

The ornamental design for a vest for ladies' blouses, substantially as shown.

JOHN H. MUMAW.

Witnesses:
